UNITED STATES PATENT OFFICE

JACOB E. BRUBAKER, OF LANCASTER, PENNSYLVANIA, ASSIGNOR TO THE HUBLEY MANUFACTURING CO., OF LANCASTER, PENNSYLVANIA, A CORPORATION OF PENNSYLVANIA

TOY VEHICLE

Application filed October 24, 1932. Serial No. 639,368.

This invention relates to toy vehicles, and more particularly to toys of the type including a chassis adapted to receive different forms of bodies.

5 While I am aware that toys having a detachably interlocked chassis and body have been heretofore made, nevertheless the locking means used is open to various objections, such for example, as difficulty in manipulation, separation of the locking parts which cause them to be lost, and the danger of injury to the child in manipulating the locking means to effect the change of bodies.

10 Accordingly, one of the objects of the invention is to provide a simple, practical and reliable means for detachably locking the body to the chassis which will be easy and convenient to operate, and safe in its functioning.

15 A further object of the invention is to provide a novel locking means which secures the body and chassis together under spring tension so as to avoid any looseness or rattling of the parts and also to prevent rattling of 20 the axles in their mountings.

25 With the above and other objects in view, which will more readily appear as the nature of the invention is better understood, the same consists in the novel features of construction, combination and arrangement of parts hereinafter more fully described, illustrated in the accompanying drawing and defined in the appended claims.

30 A preferred and practical embodiment of 35 the invention is shown in the accompanying drawing, in which:

Figure 1 is a longitudinal sectional view of a toy embodying the present improvements.

40 Figure 2 is a bottom view of the assembled device.

Similar reference characters designate corresponding parts throughout the several figures of the drawing.

45 Referring to the drawing, the chassis of the toy is designated generally as C, the same being provided with the bearings 1-1 and 2-2 for receiving the axles A on which the wheels W are mounted. The chassis may be 50 made of a casting and is preferably of such

form and size as to readily receive bodies of different type, an example of one type of body being shown in the drawing and designated as B. It will, of course, be understood that the body B may assume the form of a 55 touring car, coupé, truck, fire engine, or the like, so as to diversify the range of changes or combinations adapted to be made with a standard chassis.

The body B is preferably provided at its 60 medial portion with a hook or keeper element 3, the same being adapted to cooperate with a yielding and relatively elastic locking member 4. In the form of the invention shown in the drawing, the yielding member 4 is preferably in the form of a wire spring having its end portions 5-5 looped or coiled about the axles A so as to provide sufficient range of movement of the intermediate portion of the 65 spring to enable the user to engage and disengage the spring with the hook or keeper 3 to effect locking or detachment of the body 70 from the chassis.

The operation of the construction will be 75 readily apparent from Figure 1 which shows the parts in locked position. When it is desired to detach the body B from the chassis C it is simply necessary to shift the spring 4 laterally to disengage the hook 3 and the parts will separate. In connecting another 80 body to the chassis it is only necessary to reassemble a body on the chassis and then by slight finger pressure stretch or bow the 85 spring until the medial portion thereof engages over the hook 3.

When the parts are secured together as 90 shown in full lines in Figures 1 and 2, it will be apparent that the body and chassis are locked together under tension, while at the same time the axles A are placed under tension. This has proved to be very advantageous since it prevents the axles from rattling and provides as a whole a more stable 95 toy. The spring 4 is normally of greater length than the distance between the axles but when the body of the spring is engaged with the hook 3 the loops or coils 5 which engage with the axle are contracted, and, on the other hand, when the body of the spring 100 is released from the hook the loops or coils

5 expand. Thus, in effect, the spring 4 not only has inherent resiliency but at the same time has a tendency to stretch, or in other words, be sufficiently elastic to permit free 5 manipulation thereof to effect quick and easy connection of the parts, or vice versa.

Without further description it is thought that the feature and advantages of the invention will be readily apparent to those skilled 10 in the art, and it will of course be understood that changes in the form, proportion and minor details of construction may be resorted to, without departing from the spirit of the invention and scope of the appended claims.

15 I claim:

1. A toy vehicle including a chassis unit having wheeled axles, a body removably mounted on the chassis unit, a keeper member on the body, a spring wire having its ends connected with the axles and its intermediate portion being engaged with said keeper member on the body.

2. A toy vehicle including a chassis unit having wheeled axles loosely fitted in the 25 chassis, a body removably mounted on the chassis, and common means for holding the axles against the sides of their mountings in the chassis and also locking the body to the chassis.

3. A toy vehicle including a chassis unit having wheeled axles, a body removably mounted on the chassis and having a keeper hook, a spring having its end portions coiled about said axles, and the intermediate portion of said spring being removably engaged with the hook on the body.

4. A toy vehicle including a chassis unit having wheeled axles, a body removably mounted on the chassis, an elastic member 40 having its ends fitted to the axles and the intermediate portion of said member being removably engaged with the body.

5. A toy vehicle including a chassis unit having spaced wheeled axles, a body removably mounted on the chassis, and a yielding member having its ends fitted to said spaced axles, and the intermediate portion of said yielding member being detachably engaged with a part of the removable body.

50 6. A toy vehicle including a chassis unit having wheeled axles, a body removably mounted on the chassis, and a yielding member mounted on the axles and detachably engaged with the body.

55 7. A toy vehicle including a chassis unit having wheeled axles, a body removably mounted on the chassis, an elastic connector member mounted on the axles and detachably engaged with a part of the body.

60 In testimony whereof I hereunto affix my signature.

JACOB E. BRUBAKER.
